SKI BINDING

Adrian Berchtold Lanz, Zurich, Switzerland

Application July 30, 1942, Serial No. 452,940
In Switzerland May 18, 1942

3 Claims. (Cl. 280—11.35)

The cause of nearly all fractured legs and sprained knees and ankles in skiing is the fact that, when the skier falls, his foot, which is held fast in the toe clamp of the binding, is often forced into positions beyond the natural range of the foot and knee joints or beyond the power of resistance of the leg. This overstrain on the resistance of the leg or the knee is mainly due to the rigidity of the binding in respect of a turning of the foot about a vertical axis. A fall caused by crossing of the skis results in at least one or even more violent twists of the feet, since the binding cannot yield in the required direction.

The present invention aims at obviating this evil by providing the ski with a toe binding which is capable of turning in the horizontal plane, for instance, about a vertical axis. When a certain resistance is overcome the toe clamp can now swivel round into a position transverse to the ski itself.

The fitting of the toe clamp is most advantageously carried out in such a way that, when the weight of the skier is on the binding plate, the resistance of the toe clamp to torsion is so great that all turns and swings can be executed without any danger of swivelling the binding, while, when there is no weight on the ski, which is always the case at the moment of a fall, the resistance of the toe clamp of binding to torsion, which it is necessary to overcome, is never greater than the resistance of the leg. As soon as a certain tensile strain is exerted by the foot held in the toe clamp, the binding can be swivelled on the axis of the toe clamp without resistance. The latter case frequently presents itself when a ski sticks in wet snow.

A possible form of execution for the object of the invention is shown by way of example in the drawing. This illustrates:

Fig. 1 a longitudinal section of the portion of the ski to which the binding is affixed, with the toe clamp in its normal position,

Fig. 2 the same longitudinal section after the release of the spring check,

Fig. 3 a horizontal section of Fig. 1, and

Fig. 4 a detailed variant.

The example of a possible form of execution of the ski binding shown is provided with a round binding plate 1, which carries the ski binding and is screwed on to the ski 2. This binding plate has on its under-side a central pivot socket 3 which fits into a corresponding hole bored into the ski. On its upper side binding plate 1 has a collar 4 on the same axis as socket 3 but of smaller diameter. This collar forms the axis of a turn-

table 5 which can turn on the binding plate 1 and which, together with an easily removable covering plate 6 attached to it, forms the base of the toe clamp into which fits one clamp jaw 7 on each side, this jaw being adjustable by means of teeth 8 or capable of being fixed in the desired position by means of screws 9. 5' is the guide rim of turntable 5 which overlaps the rim of the binding plate. 10 designates the binding attached to the jaws 7 of the toe clamp. The normal position of jaws 7 of the toe clamp is arrived at by means of a checking device which yields at a certain pressure. This check is formed by indentations 11 provided in the under-side of turntable 5 and by catches 12 provided on binding plate 1 which engage indentations 11. Bolt 14, with its head plate 13, is positioned in collar 4, and the inside end of this bolt can be screwed into a bush 15 by means of a thread 14'. The bush 15 can be moved lengthwise in pivot socket 3 and is secured against twisting by peg 15' introduced into a lengthwise slit 16 in socket 3. By means of a pressure spring 17, which presses at one end against bush 15 and at the other against the step 25 3a of collar 4, the head plate 13 of the bolt 13 is pressed down against its seat sunk in the base of toe clamp 5, 6. It follows that toe clamp base 5, 6 can only rise from the binding plate 1 counter to the pressure action of spring 17, and this rising releases the checking device. By tightening bolt 14 to a greater or less degree the tension of spring 17 can be adjusted between 20 and 30 kgs. approx. When the weight of the body is on the ski, the resistance to the swivelling of toe clamp 5, 6 which has to be overcome in order to release the check is so great that the device remains securely engaged even when the most diverse turns and swings are executed. When the weight is removed or almost completely removed from the ski, as occurs in the case of a fall, the checking device yields to the strong torsion of the foot in the toe clamp before the powers of resistance of the leg are exceeded. If during a fall a tensile force counter to the pressure of spring 17 is exerted by the foot on the toe clamp, then the release of the check is possible with very slight resistance to torsion. By means of the swivelling of the toe clamp, i. e. of the binding, made possible by the overcoming of a certain resistance 30 as described above, the danger of breaking a leg or straining a leg joint in a fall is greatly diminished.

In the variant shown in Fig. 4 turntable 5 is equipped with a rim 5'' which bends inwards and 55 which, while leaving a certain margin of play,

grips a projecting rim 1' of the binding plate, so that the lifting movement of the toe clamp 5, 6 from the binding plate 1, which is necessary for the release of the checking device, is limited by rim 5".

It will be obvious to those skilled in the art that various changes may be made in this invention without departing from the spirit thereof, and the invention is not limited to what is shown in the drawing and described in the specification, but only as indicated in the appended claims.

I claim:

1. A ski binding comprising in combination with a ski, a binding plate rigidly attached to the ski, a toe clamp having a base plate movably mounted on the binding plate and adapted for rotation in a horizontal plane, means for normally resisting rotary movements of the base plate and a spring for forcing the base plate into holding engagement with the binding plate. 15

2. A ski binding comprising in combination with a ski, a binding plate rigidly attached to the ski, a toe clamp having a base plate movably mounted on the binding plate and adapted for rotation in a horizontal plane, means for normally resisting 20

rotary movements of the base plate, a spring for forcing the base plate into holding engagement with the binding plate and means for adjusting the tension of the spring whereby the resistance offered by the rotary movement resisting means may be varied.

3. A ski binding comprising in combination with a ski, a binding plate rigidly attached to the ski, a toe clamp having a base plate movably mounted on the binding plate and adapted for rotation in a horizontal plane, means for normally resisting rotary movements of the base plate, a spring for forcing the base plate into holding engagement with the binding plate, the ski having an opening therein beneath the binding plate, a tubular boss depending from the binding plate and disposed in said opening, said spring being coiled and located in said tubular boss, a headed screw passing downwardly through said plates and coiled spring and terminating in said boss and a bushing in the boss into which the lower end of the screw is threaded, the headed bushing being longitudinally movable in the boss and restrained from rotary movements.
